BASE PLATE FOR BASEBALL DIAMONDS

John O. Seys, Chicago, Ill., assignor to The Seamless Rubber Company, Inc., New Haven, Conn., a corporation of Massachusetts

Application November 4, 1936, Serial No. 109,127

2 Claims. (Cl. 273—25)

This invention relates to base plates for baseball diamonds, and more particularly to the base plate used at the base at which the batter stands, usually known as "home plate".

It is common practice at the present time to provide at "home plate" a base plate permanently secured in place, while the "bags" or bases at the other three corners of the diamond are usually removable. This home plate is of somewhat peculiar configuration, and is, of course, of standard size. It has been the custom in the past to make these bases of rubber or some flexible material, and as they are embedded in the ground to some extent, they are of substantial thickness. The result is that, although the top of the plate is presumably flush with the ground, the dirt about the plate often becomes dug up or removed in one way or another, so that a sharp projecting edge remains; that is, the base plate will project abruptly from the ground at its edge, and becomes a source of possible serious injury to players in that they are quite likely to be tripped if their toes or spikes catch thereon.

It is necessary, however, for the base plate to have a sharply defined edge or surface of the proper size in order that the outer edges may be readily distinguished by the players and umpire, and not confused with the surface of the baseball diamond or any surrounding material.

One object of the present invention is to eliminate the disadvantage referred to above, and to provide a base plate which will have no abrupt projecting edges, but will at the same time have a sharply defined base portion of the proper dimensions which will be clearly distinguishable.

Another object of the invention is the provision of a home plate for baseball diamonds having a central portion of the proper size and dimensions, and a border or surrounding portion providing a beveled edge whereby any abrupt projecting side edges of the plate will be eliminated.

A still further object of the invention is the provision of a base plate for baseball diamonds having a central portion of the standard dimensions and a surrounding beveled border portion, the latter being of a color contrasting to that of the plate proper and being separated from the plate proper by a sharp line of demarcation.

Still another object of the invention is the provision of a base plate provided with reinforcing means to prevent the plate warping or buckling when in use.

To these and other ends the invention consists in the novel features and combinations of parts to be hereinafter described and claimed.

In the drawing:

Fig. 1 is a top plan view of a base plate embodying my invention;

Fig. 2 is a sectional view on line 2—2 of Fig. 1; and

Fig. 3 is a view similar to Fig. 2 showing a modified form of my invention.

To illustrate a preferred embodiment of my invention, I have shown in Fig. 1 a base plate having a central or main portion 10 of the standard size and dimensions required by the rules of the game. The home plate required by the present rules is of a peculiar shape, being a five-sided figure, seventeen inches across at its widest point, and likewise seventeen inches from the apex to the base of the figure. The portion 10 will conform to these dimensions, and will preferably be of white rubber so that its outline may be readily distinguished by both umpire and players. It will be understood that the portion 10 of the plate shown in the drawing is the same form and size as the plate in use at the present time. If, however, the usual plate is employed, the thickness of the plate will cause it to project from the ground to some extent, and as the sides of the plate are strictly vertical, these projecting sides are apt to trip a player or base runner and thus effect a possible serious injury.

To avoid such a possibility I provide about the plate a beveled edge or border 11. This border 30 may extend, as shown, entirely about the plate proper 10, but will preferably be of a color readily distinguishable from the central portion 10 of white rubber, so that it will not have the effect of adding anything to the dimensions of the base 35 when used upon the playing field. This beveled border 11 tapers outwardly, as shown more particularly in Fig. 2, to a relatively sharp edge 12, so that when the plate as a whole is embedded in the ground, the border 11 will be covered by 40 the dirt of the baseball diamond. If, however, this dirt becomes carried away for any reason, no sharp abruptly projecting edges will be exposed due to the sloping surface of the border 11, so that there will be nothing upon which a base 45 runner or player can catch his shoe or spikes.

The border portion 11 will preferably be of a dark color, usually black, and may be formed integrally with a lower portion 13 of the base plate, which lies below the white rubber slab 10. That is, in this instance the base plate may consist of two layers, the upper white layer 10, and a lower black or dark-colored layer 13, the latter being carried outwardly beyond the edges of the layer 10 and having beveled edges to provide a beveled 55

border around the portion 10, the inner edge of this border being, of course, flush with the upper surface of the portion 10. In another aspect of the invention the plate may be considered of 5 a lower foundation part 13 having a beveled edge 10, and having a recess in its upper surface to receive the white portion or base plate proper 10, whereby the latter is seated within the former 10 so that its surface is flush with the upper edge of the surrounding border.

In order that there may be a sharp line of demarcation between the dark colored border 11 and the adjacent edge of the base plate proper 10, there may be a slight space 14 left between 15 these two parts. This is particularly desirable if the base plate is formed as a whole in a mold and vulcanized, for in such case the light and dark rubber of the portions 10 and 11 might otherwise run together to some extent, so that 20 the line between them would not be sharply defined.

As stated, such plates are usually permanently 25 fixed in place, and to this end washers or collars 16 may be embedded or molded in the body of the plate, these members being provided with 30 threaded openings 17 to receive the pins or spikes 18, which are adapted to be driven into the ground.

It sometimes occurs that such plates tend to 35 warp or buckle after being subjected to use, and in Fig. 3 of the drawing I have shown a modified form of my invention, which is designed to prevent such action. This modification of the invention is of the same form and configuration 40 as the plate shown in Figs. 1 and 2. Embedded in the material of the plate, however, is a sheet of metallic material 19 of relatively heavy gauge, such as sheet metal of twelve-gauge thickness,

for example. This may be molded into the rubber base portion of the plate, and it will cause the plate to lie flat at all times and prevent any tendency thereof to buckle. In this case the washers or collars 16^a to receive the pins 18 may be secured to this plate as by welding, for example, so that these washers will be firmly secured in place.

While I have shown and described some preferred embodiments of my invention, it will be understood that it is not to be limited to all of the details shown, but is capable of modification and variation within the spirit of the invention and within the scope of the appended claims.

What I claim is:

1. A base plate for baseball diamonds or the like, said plate comprising a flat body having beveled outwardly tapering edges, said body being provided with an upwardly facing recess extending between said beveled edges, and a sheet of material of a color contrasting with the body portion disposed in said recess.

2. A base plate for baseball diamonds comprising an outer border portion, said portion being beveled and diminishing in thickness toward its outer edge to form a thin edge adapted to be embedded in the ground, a slab-like portion within the border, the upper surface of which is substantially flush with the inner edge of the border portion, said slab-like portion being of the standard dimensions of a base plate and of a color contrasting with that of the border, and said inner portion being spaced from the border portion at the upper surface of the plate to provide a sharp line of demarcation therebetween.

JOHN O. SEYS.
